United States Patent

Des. 238,137
Patented Dec. 23, 1975

238,137

CANISTER OR THE LIKE

James B. Swett, Barrington, R.I., assignor to Dart Industries Inc., Los Angeles, Calif.

Filed July 25, 1974, Ser. No. 491,887

Term of patent 14 years

Int. Cl. D7—06

U.S. Cl. D7—79

FIG. 1

FIG. 2

FIG. 3

FIG. 4

FIG. 5

FIG. 1 is a top perspective view of a canister or the like showing my new design;

FIG. 2 is a top plan view thereof;

FIG. 3 is a front elevational view thereof;

FIG. 4 is a side elevational view thereof; and

FIG. 5 is a bottom plan view thereof.

I claim:

The ornamental design for a canister or the like, substantially as shown.
